UNITED STATES PATENT OFFICE.

PERRY O. RESTEIGEN, OF BRODHEAD, WISCONSIN.

CABLE-HOLDER FOR MANURE-CARRIERS.

1,202,102.

Specification of Letters Patent. Patented Oct. 24, 1916.

Application filed May 6, 1916. Serial No. 95,991.

To all whom it may concern:

Be it known that I, PERRY O. RESTEIGEN, a citizen of the United States, residing at Brodhead, in the county of Green and State 5 of Wisconsin, have invented certain new and useful Improvements in Cable-Holders for Manure-Carriers, of which the following is a specification.

My invention relates to new and useful 10 improvements in cable holders and more particularly in cable holders for manure carriers, the primary object of my invention being the provision of a cable holder which may be attached to a barn wall above the 15 doorway and which will support a cable forming a track for the manure carrier.

A further object of my invention is to so construct the holder that it may be raised or lowered to hold the cable above the door or 20 at some point in the doorway, as desired.

In this connection, a still further object of my invention consists in the provision of means for automatically locking the holder in raised position, and in means for preventing turning of the holder when in lowered 25 position.

With these and other objects in view, my invention will be more fully described, illustrated in the accompanying drawing, and 30 then specifically pointed out in the claims which are attached to and form a part of this application.

In the drawing: Figure 1 is a perspective view of my invention; Fig. 2 is a side elevation of my invention in use, one wall of a barn being shown in section.

Corresponding and like parts are referred to in the following description and indicated in all the views of the drawing by the same 40 reference characters.

In order to insure a clear and accurate understanding of my invention I have illustrated it in connection with one wall 10 of a barn or other structure having a doorway 11 which may be closed by a door 12.

My invention includes a guiding and supporting sleeve 13 adapted to be mounted in vertical position above the doorway 11 and a holder or hanger 14 mounted in the sleeve.

50 The sleeve, at its ends, is formed with laterally directed ears 15 which may be engaged against the wall 10 and through which may be passed screws 16 or other suitable fastening devices to secure the sleeve in place.

55 The sleeve is further secured in place by a clamping collar 17 mounted about the inter-

mediate portion of the sleeve and having laterally extending ears 18 through which is passed a clamping bolt 19 by means of which the collar may be secured about the 60 sleeve. A bolt 20 is passed through the intermediate portion of the collar and through the wall of the building and secured by a nut 21 to hold the collar against longitudinal movement along the sleeve. Diagonally 65 extending braces 22 are secured at their outer ends to the ears 18 by the same bolt 19 employed in clamping the ears together and at their free ends are attached to the wall 10 by any suitable fastening devices. 70

A locking lever 23 is pivoted adjacent one end between the ears 18 and is formed with a hooked terminal 24 adapted to pass through an opening 25 formed in the sleeve 13 and to engage in a notch 26 formed in the 75 hanger 14, the hook being urged to this position by a leaf spring 27, one end of which is clamped between the ears and sleeve and the other end of which is bifurcated to receive the free end of the lever 23. 80

The hanger 14 is in the form of a rod proportioned to slidably engage in the sleeve and provided at its lower end with an offset arm 28 having an upwardly directed terminal 29. This terminal 29 has its upper face 85 grooved to form a seat for the cable 30 which the device is to support, this cable being secured to its seat by a U-shaped band 31 fastened about the cable and terminal 29, as shown at 32. The wall 10 above the door 90 opening is cut-away, as shown at 33, to form a space for the cable 30 when the holder is in elevated position, this being clearly shown in Fig. 1. The upper end of the rod or hanger 14 is provided with a diametrically 95 extending pin 34, the ends of which engage in seats 35 formed by notching the upper end of the sleeve 13 when the holder is in lowered position in order to prevent any 100 turning movement of the holder.

If desired, the wall may be formed with a second opening 33' at that side of the holder opposite the opening 33 in order that the holder may be swung to the other side, thus permitting the positioning of the cable 105 at either side of the doorway. If such is the case, the hanger 14 is generally provided with a second notch 26' corresponding to the notch 26 and engageable by the hook 24 when the holder is raised. 110

From the foregoing description, taken in connection with the drawing, the operation

of my improved cable holder will be readily understood. Under normal circumstances, that is when the manure carrier is not being used, the cable will be held in the position shown in Fig. 1. At any time the cable is desired for use, the lever 23 will be swung against its spring to release the hanger 14 and lower the cable to the proper level. When so lowered, the pin 34 engaging the 10 seats 35 will not only prevent further downward movement of the holder, but will also prevent any swinging movement thereof. After use, the holder may be pushed upwardly until the notch 26 registers with the 15 opening 25 of the sleeve when the hook 24 will immediately and automatically lock the holder in place.

Having thus described the invention, what is claimed as new is:

20 1. A cable holder for manure carriers including a support, a cable holding member slidably mounted in the support, and means for automatically locking the member in raised position, said means including a spring pressed lever having a hooked terminal engageable in a seat formed in the member.

25 2. A cable holder for manure carriers including a tubular guide sleeve adapted for attachment to the wall of a building, a member slidable in the sleeve and having a laterally directed arm formed with an upwardly directed cable receiving terminal, means for limiting the movement of the member in either direction, and means for locking the member in raised position.

30 3. A cable holder for manure carriers including a guide sleeve adapted for attachment to a building wall above the door opening thereof, a clamping collar mounted about the sleeve and adapted for attachment to the said building wall, a spring pressed lever pivoted upon the collar and having a hooked terminal adapted to project through an 35 opening formed in the sleeve, a hanger rod reciprocally mounted in the sleeve and having a seat adapted to receive the hooked terminal of the lever when the rod is in raised position, means at the lower end of the rod for supporting a cable, and means for limiting the downward movement of the rod.

40 4. A cable holder for manure carriers including a guide sleeve adapted for attachment to a building wall above the door opening thereof, a clamping collar mounted above the sleeve and adapted for attachment to the said building wall, a spring pressed lever pivoted upon the collar and having a hooked terminal adapted to project through an 45 opening formed in the sleeve, a hanger

rod reciprocally mounted in the sleeve and having a seat adapted to receive the hooked terminal of the lever when the rod is in raised position, means at the lower end of the rod for supporting a cable, and means for limiting the downward movement of the rod, said means also holding the rod against turning movement when in lowered position. 70

5. A cable holder for manure carriers including a guide sleeve adapted for attachment to a building wall above the door opening thereof, a clamping collar mounted above the sleeve and adapted for attachment to the said building wall, a spring pressed lever pivoted upon the collar and having a hooked terminal adapted to project through an opening formed in the sleeve, a hanger rod reciprocally mounted in the sleeve and having a seat adapted to receive the hooked terminal of the lever when the rod is in raised position, means at the lower end of the rod for supporting a cable, and means for limiting the downward movement of the rod, 75 said means also holding the rod against turning movement when in lowered position and including a pin passed through the rod and engageable in notches formed in the upper end of the sleeve. 90

6. A cable holder for manure carriers including a guide sleeve adapted for attachment to a building wall above the door opening thereof, a spring pressed lever pivoted in juxtaposition to the sleeve and having a terminal adapted to project through an opening in the sleeve, and a hanger rod reciprocally mounted in the sleeve and having a seat adapted to receive the terminal of the lever in one position of the hanger. 100

7. A cable holder for manure carriers including a guide sleeve adapted for attachment to a building wall above the door opening thereof, a hanger rod reciprocally mounted in the sleeve, means for automatically locking the hanger rod in elevated position, and means coöperating between the rod and sleeve to hold the rod against turning movement when in lowered position. 105

8. A cable holder for manure carriers including a guide sleeve adapted for attachment to a building wall above the door opening thereof, a hanger rod reciprocally mounted in the sleeve, means for automatically locking the hanger rod in elevated position, and means coöperation between the rod and sleeve to hold the rod against turning movement when in lowered position, 110 said means also limiting the downward movement of the rod. 115

In testimony whereof I affix my signature.
PERRY O. RESTEIGEN. [L.S.]
